UNITED STATES PATENT OFFICE.

EDWARD B. THOMAS, OF CINCINNATI, OHIO, ASSIGNOR OF ONE-FOURTH TO EDWARD DISHER AND ONE-FOURTH TO SYDNEY W. WILLIAMSON, BOTH OF CINCINNATI, OHIO:

TRACTION DEVICE FOR AUTOMOBILES.

Application filed December 19, 1923. Serial No. 681,477.

To all whom it may concern:

Be it known that I, EDWARD B. THOMAS, a citizen of the United States, and resident of Mount Washington, Cincinnati, Ohio, have invented certain new and useful Improvements in Traction Devices for Automobiles, of which the following is a full, clear, and exact description, reference being had to the accompanying drawings, forming 10 a part of this specification.

My invention relates to traction devices for automobiles, and has for its principal object, the provision of a simple and efficient traction device whereby traction may 15 be provided for a motor vehicle so that it is enabled to get out of a rut, mud-hole or other situation, where the natural surface does not provide the required traction.

A further object of the invention is to 20 provide a device of the character mentioned of such construction that the same may be compactly folded or rolled for convenient carriage when not in use.

Other objects of the invention will appear 25 from the following detailed description thereof.

In the drawings:—

Figure 1 is an edge elevation of my new 30 traction device;

Figure 2 is a plan view of the same;

Figure 3 is a plan view showing the operation of the device;

Figure 4 is a side view illustrating the use and operation of the device.

The numeral 1 indicates a pad, the casing of which is preferably constructed of canvas or similar fabric. One end of the pad 1 is provided with a loop 2 within which a metal tube 3 is secured. The other end of the pad 1 is tapered as shown at 4 in Figure 2.

The numeral 5 indicates a pad, the same being constructed preferably of a number of laminations of canvas or other suitable material. One end of the pad 5 is provided with a loop 6 within which a metal tube 7 is secured. The pad 5 flares outwardly away from the loop 6 as clearly shown in Figures 2 and 3 of the drawings. A rope 45 or cable 8 of suitable dimension to be threaded through the tubes 3 and 7 is provided for the purpose of connecting the pads 1 and 5 when in use.

In Figures 3 and 4 the operation of the

device is illustrated. When the natural surface 9 is of such a nature that insufficient traction is provided for the rear wheel 10 of a vehicle to enable it to move the vehicle forward, the pad 1 is placed with the end 4 as far under the wheel as possible without jacking the wheel up. The pad 5 is then placed in front of the front wheel 11 of the vehicle, and the two pads are connected by threading the rope 8 through the tubes 3 and 7 and tying the ends as shown at 12. The vehicle is then started to move forward. The rear wheels are thus rotated in the direction of the arrow in Figure 4. This movement of the wheel 10 will tend both to carry the vehicle forward and also to draw the pad 1 under the wheel; the latter tendency, were the movement of the pad unrestrained, would in many cases cause the pad to be moved backwardly from under the wheel without accomplishing any beneficial result in moving the vehicle itself. This action is however prevented by the holding action of the front wheel 11 on the pad 5, which obviates the possibility of the pad 1 being drawn too far backwardly. The flaring of the pad 5 will permit the turning of the front wheel without releasing the pad. The metal tubes prevent buckling of the pads lengthwise.

It will be noted therefore that in the above construction a traction device has been provided in which the efficiency of the pad 1 is assured by reason of a holding pad secured by the front wheel of the vehicle itself. The rope or cable is, of course, of such a length that the device may be adapted to cars of different wheel bases and also to the various conditions of surface which may arise. It will further be noted that when not in use, the device may be compactly rolled or folded, the pads and connecting rope being of course, entirely flexible, and thus the device may be conveniently stored in the vehicle at all times for use in cases of emergency.

Having thus fully described my invention what I claim as new, and desire to secure by Letters Patent is:—

1. A traction device comprising a traction member adapted to be placed in relation to the rear wheel of a vehicle so as to afford traction therefor, a member arranged to be secured by the front wheel of

- 2 said vehicle, and means variable in length for securing said members together when in position.
2. A traction device comprising a flexible 5 pad adapted to be placed in relation to the rear wheel of a vehicle so as to afford traction therefor, a flexible pad arranged to be secured by the front wheel of said vehicle, and means variable in length for securing 10 said pads together when in position.
3. A traction device comprising a flexible pad adapted to be placed in relation to the rear wheel of a vehicle so as to afford traction therefor, a flexible pad arranged to be 15 secured by the front wheel of said vehicle, and means variable in length for securing said pads together when in position.
4. A traction device comprising a flexible pad adapted to be placed in relation to the 20 rear wheel of a vehicle so as to afford traction therefor, a flexible pad arranged to be secured by the front wheel of said vehicle,
- means variable in length for securing said pads together when in position, and means for preventing said pads from longitudinal 25 buckling.
5. A traction device comprising a flexible pad adapted to be placed in relation to the rear wheel of a vehicle so as to afford traction therefor, a flexible pad arranged to be 30 secured by the front wheel of said vehicle, means variable in length for securing said pads together when in position, and means for preventing said pads from longitudinal 35 buckling.
6. A traction device comprising a pair of pads, a metal tube secured in one end of each pad, and means adapted to be threaded through said tubes to secure the pads together in corresponding relation to the 40 travel of the rear and front wheels respectively of a motor vehicle.

EDWARD B. THOMAS.
